PUMP FOR PASTY MASSES, AS CONCRETE

Fritz Hell, Kiel, Germany; vested in the
Alien Property CustodianApplication September 13, 1940, Serial No. 356,697
In Germany October 13, 1939

3 Claims. (Cl. 103—140)

This invention relates to a circulating pump for pasty masses, especially concrete. It has for its object to provide a construction which is simple and reliable in service and not endangered even by the stones contained in the concrete. The invention consists of a cylindrical casing with a cylindrical piston rotating therein and with slide plates adapted to be oscillated out of the piston and serving as conveying means. The piston is concentrically located in the casing and the slide plates are carried within recesses or indentations which are formed in the periphery of the piston to extend transversely across the periphery and which are uniformly positioned around the piston. A cylindrical plate or disc is fixed on each end of each slide so that when the slides are mounted in the piston these discs close the ends of the indentations in which the slides are located.

The arrangement is further made that, in order to carry out a drive of the slide plates, the cylindrical discs which engage on the slide plates carry outwardly projecting pins fixed on the side walls of the piston. On at least one of these pins a control lever for the slide plates may be mounted.

The invention contemplates oscillating each slide by a spring controlled lever which is attached to one end of the slide to rotate with the pump piston and which is operated by a cam or guide track on the pump casing against which one of its ends is resiliently held. The resiliency in the means for oscillating the slides helps to avoid damage to the same from stones wedging in the casing and allows the slide and its control elements to be made of comparatively light gauge or light weight material.

The slide plate has preferably the shape of a plate extending over the passage cross section of the pump and curved and mounted in the piston so that in the opening position it fits snugly in the outer circumference of the piston. The plate is journalled in the piston preferably by lateral discs made in one piece and connected therewith.

An embodiment of the invention is illustrated by way of example in the accompanying drawing, in which

Fig. 1 is a vertical cross-sectional view through the pump, Fig. 2 is a horizontal sectional view through the pump,

Fig. 3 is a front elevation of the piston pump.

The stationary pump casing is designated by 1 and the piston rotating in the direction of the arrow 3 is designated by 2. The piston 2 is keyed on the driving shaft 4 journalled in lateral bearings 5.

The rotary slides are mounted in the piston which has indentations 6. The rotary slides consist of slide plates 7 extending over the passage cross section of the pump and carrying at their ends discs 8 from which pins 9 extend which are journalled in brackets 10 fixed on the piston. The outer side 11 of the rotatable discs 7 are curved so that they fit flush into the circumference of the piston 2 when the slide is in the open position shown in the lower portion of Fig. 1.

Two-armed levers 12 are fixed on one side of the pump on the journalled pins 9 of the rotary slides and carry a roller 13 on the outer arm, whereas a pull spring 14 is hooked onto the end of the other arm, the other end of the spring being fixed on the piston at 15. The rollers 13 roll on a guide rail 16 fixed on the outer side of the stationary pump casing by screws 17.

The operation of the pump is as follows:

The material is fed to the pump by a funnel 18 and drops into the conveying channel 19 of the pump which is bordered by the stationary pump casing and by the piston 2. The material is then displaced by a rotary slide rotating with the piston when the plate 7 is in the transverse position relative to the outlet 20 as shown in Fig. 1 at least up to the moment when the plate 7 of the next following rotary slide has shut off the connection of the space behind the plate of the rotary slide in front of it with the admission point 18. The slide is then opened by the co-operation of the two-armed lever 12 with the roller 13 and the control rail 16, and the plate 17 arrives finally in the extreme open position shown in the bottom portion of Fig. 2, in which the passage to the outlet 20 is free. When the slide, i. e. the plate 7, has passed along the stripper 21 fixed on the casing wall, it is returned into its closing position by the action of the spring 14 according to the construction of the control rail, and the operation begins anew.

The invention is evidently not restricted to the embodiment illustrated, as this may be constructively modified within the range of the invention; for instance more than two rotary slides may be mounted in the piston and special devices may be provided at the different points for a perfect packing of the conveying channel against the outer side, for instance on the side discs 8.

I claim:

1. Circulating pump for concrete and other pasty material comprising a casing with a cylindrical bore extending therethrough from side to side, a cylindrical rotor arranged in the cylindrical bore concentric therewith and forming an an-

nular pumping chamber between the cylindrical surfaces of the casing and rotor, an inlet port to said chamber of cross-section substantially equal to that of the annular chamber, an outlet port from said chamber of similar cross-section spaced circumferentially of said chamber from said inlet port, means in said chamber between the inlet and outlet ports for preventing direct movement of material from one to the other of the ports, side flanges on said rotor closing the sides of the annular chamber, at least one pump blade arranged in a peripheral recess in said rotor, said blade being oscillatable between a position in which it projects into contact with the cylindrical bore of the casing and a position in which it is retracted within the periphery of the rotor, side flanges on said blade closing circular openings in the side flanges of the rotor, cam and resilient operating means for retracting and extending said pump blade.

2. Circulating pump according to claim 1, in which the blade is pivoted intermediately of its depth about an axis lying in the circumference of the rotor.

3. Circulating pump for concrete and other pasty material comprising a casing with a cylindrical bore extending therethrough from side to side, a cylindrical rotor arranged in the cylin-

drical bore concentric therewith and forming an annular pumping chamber between the cylindrical surfaces of the casing and rotor, an inlet port to said chamber of cross-section substantially equal to that of the annular chamber, an outlet port from said chamber of similar cross-section spaced circumferentially of said chamber from said inlet port, means in said chamber between the inlet and outlet ports for preventing direct movement of material from one to the other of the ports, side flanges on said rotor closing the sides of the annular chamber, at least one pump blade arranged in a peripheral recess in said rotor, said blade being oscillatable between a position in which it projects into contact with the cylindrical bore of the casing and a position in which it is retracted within the periphery of the rotor, side flanges on said blade closing circular openings in the side flanges of the rotor, cam and resilient operating means for retracting and extending said pump blade, said means including an actuating lever pivoted intermediately of its length to the pump blade, a roller on one end of said lever, a cam track on the casing engaging said roller, and a spring connected between the rotor and the other end of said lever.

FRITZ HELL.
